UNITED STATES PATENT OFFICE.

EMIL M. DEAN, OF ALTA, CALIFORNIA.

STAPLE-DRIVER.

SPECIFICATION forming part of Letters Patent No. 405,537, dated June 18, 1889.

Application filed February 15, 1889. Serial No. 300,047. (No model.)

To all whom it may concern:

Be it known that I, EMIL M. DEAN, a citizen of the United States, residing at Alta, in the county of Placer and State of California, 5 have invented a new and useful Improvement in Staple-Drivers, of which the following is a specification.

My invention relates to an improvement in staple-drivers; and it consists in certain novel 10 features, hereinafter described and claimed.

In the accompanying drawings, Figure 1 is a perspective view. Fig. 2 is a vertical longitudinal section of the same. Fig. 3 is a detail view of the guide for the plunger, and 15 Fig. 4 is a detail perspective view of the staple-guide. Fig. 5 is a detail perspective view of the plunger.

Referring to the drawings by letter, A designates the body, which is made in two members, the larger member having the longitudinal groove B, in which the driving-rod C works. The said driving rod or plunger is provided at an intermediate point of its length with an annular shoulder or stop D, which is 20 adapted to limit the play of the driving-rod by contacting with the upper end of the body and also with the end of the guide E, as shown. 25 Fig. 4 is a detail perspective view of the staple-guide. Fig. 5 is a detail perspective view of the plunger. This guide E consists of a metallic arm or bracket having its lower end provided with a longitudinal slot, through which the securing-bolt passes to adjustably secure it to the body, and has its upper end bent inward and provided with a notch G, through which the driving-rod passes, as shown. The smaller 30 or front section of the body is provided in its lower end with a longitudinal slot or notch H, and the staple rack or guide I has its lower end entering said notch, so that the staples will be guided thereinto, and thereby brought 35 into position below the end of the driving-rod. The staple rack or guide consists of a small plate, which extends outward from the body and is curved to one side, as shown. At its inner or lower end the rack is provided with the lateral wings, which are placed 40 against the front side of the body, and through which the securing-bolts are passed to fasten the guide to the body. On the sides of the guide, at the inner or lower end of the 45 same, I secure the inwardly and downwardly 50

curved ribs I², which serve to guide the staples positively into position beneath the driving-rod and hold them upright until forced home by the said rod.

J designates a staple-holder, which is pivoted between two lugs K on the front side of the body, and conforms to the staple-rack, so as to hold the staples thereon. In practice the staples are placed on the guide-rack, and will slide down the same through the slot H into position beneath the driving-rod. The device is then placed over the point at which it is desired to drive the staple, and the driving rod or plunger is then given a sharp blow, so as to force the staple home. 65 The driving-rod is then raised, and the next staple will automatically slide into position to be operated upon.

From the foregoing description, taken in connection with the accompanying drawings, 70 it will be seen that I have provided a very efficient and easily-operated device by means of which staples can be rapidly driven home, so as to secure the screens of doors and windows in place. By suitably raising or lowering the guide E the play of the operating-rod will be adjusted to the height of the staples being used, and the guide-rack can be adjusted to the thickness of the staple by interposing packing between the same and the 75 front side of the body. The staples can be easily slipped over the upper edge of the guide-rack after the staple-holder has been raised, and after the staple-holder has been lowered will be securely held on the rack. 80

Having thus described my invention, what I claim, and desire to secure by Letters Patent, is—

1. The combination of the body having a longitudinal slot in its lower end, the driving-rod working in the body, the curved rack secured to the body and having its end entering the slot in the body, and the curved staple-holder pivoted to the body adjacent to and above the rack, as set forth. 90

2. The combination of the body having a longitudinal slot in its lower end, the driving-rod working in the body, and the rack having its end entering the longitudinal slot in the body and provided with the curved ribs on 100

its sides and with lateral flanges through which securing-screws are passed into the body, as set forth.

3. The combination of the body, the driving-rod working therein, and the guide-rack secured to the lower end of the body and entering the same and having the downwardly and inwardly curved ribs on its sides at its inner end, as set forth.

In testimony that I claim the foregoing as to my own I have hereto affixed my signature in presence of two witnesses.

EMIL M. DEAN.
